UNITED STATES PATENT OFFICE.

JOSHUA W. MAYER, OF NEW YORK, N. Y.

DESIGN FOR A RING OR SIMILAR ARTICLE.

60,559.

Specification for Design.

Patented Mar. 7, 1922.

Application filed October 8, 1921. Serial No. 506,532. Term of patent 7 years.

To all whom it may concern:

Be it known that I, JOSHUA W. MAYER, a citizen of the United States of America, residing at New York city, county, and State of New York, have invented a new, original, and ornamental Design for a Ring or Similar Article, of which the following is a specification, reference being had to the accompanying drawing, forming part hereof, in which—

Fig. 1 represents a side view of a ring embodying my new design, and Fig. 2 is an edge view thereof.

I claim:

The ornamental design for a ring or similar article, as shown.

Signed at New York city, N. Y., this 1st day of October, 1921.

JOSHUA W. MAYER.

Witnesses:

FRANK H. WELLS,
JOHN GRALTZER.
